PARING KNIFE ATTACHMENT

Charles H. Harvey, Jacksonville, Fla.

Application December 13, 1948, Serial No. 65,029

7 Claims. (Cl. 30—123)

1

This invention relates to paring knives or the like and more particularly to a means for mounting on the knife to shield the user from flying juices.

An object of this invention is to provide in combination with a paring knife, a shield and means supporting the shield along the back of the knife in a position whereby the knife blade may be used in a normal manner, and any flying juices will strike the shield.

Another object of this invention is to provide in combination, a knife and an absorbent shield supported from the handle of the knife, the shield being formed of spongy material such as sponge rubber, natural sponge or other absorbent material.

A further object of this invention is to provide as an attachment for a knife, an elongated absorbent pad and a clamping means engaging the pad and provided with means securing the clamping means to the knife whereby the pad will be disposed along the back of the knife.

This invention relates to an attachment to be used on paring knives or the like as an absorbent shield, in the peeling and preparing of onions.

With the above and other objects in view, my invention consists in the arrangement, combination and details of construction disclosed in the drawings and specification, and then more particularly pointed out in the appended claims.

In the drawings,

Figure 1 is a top plan view of an attachment for a paring knife constructed according to an embodiment of my invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 2.

Figure 5 is a detail side elevation of a modified form of this invention.

Figure 6 is a sectional view taken on the line 6—6 of Figure 5.

Figure 7 is a detail side elevation, partly in longitudinal section, of another modification of this invention.

Figure 8 is a sectional view taken on the line 8—8 of Figure 7.

Figure 9 is a detail side elevation, partly in longitudinal section, of another modification of this invention.

Referring to the drawings and first to Figures 1 to 4 inclusive, the numeral 10 designates generally a paring knife formed with a handle 11 and a blade 12.

2

In order to provide a means whereby the knife 10 may be used for peeling vegetables such as onions or the like in order that the juices emanating from the vegetables will be prevented from contacting with the user, I have provided a shield 14 which is adapted to be disposed along the back of the blade 12, being supported from the handle 11. The shield 14 is constructed of sponge like material and may be formed of either sponge rubber, natural sponge or the like, and the shield 14 is supported along the back of the knife by means of a holder generally designated as 13.

The holder 13 comprises a pair of forwardly divergent resilient bars 15 and 16. The bars 15 and 16 are connected together between the ends of the shield 14 by means of a connecting bar 17 and the bars 15 and 16 extend forwardly from a substantially U-shaped clip 18 which may be formed integral with the rear ends of the arms 15 and 16. The clip 18 is adapted to engage over the forward end of the handle 11, as shown in Figure 3, so that the device may be removably mounted on the knife 10.

The shield 14 is clamped or secured to the arms 15 and 16 by means of a pair of elongated resilient clamping bars 19 which are formed integral with the arms 15 and 16, extending rearwardly beneath the clip 18. The arms 19 may be disposed in overlapping relation, as shown in Figure 4, and these arms may be secured relative to the shield 14 and to the arms 15 and 16 by a fastening means which in the present instance is in the form of a wire 20 extended about the rear portions of the arms 15 and 16 and through the shield 14. As shown in Figure 4, the rear portion of the shield 14 will be transversely bent so as to extend downwardly toward the blade 12.

Referring now to Figures 5 and 6 there is disclosed a modified form of this invention wherein the holder 13a which is similar to the holder 13, is secured to the handle of the knife by means of a split clamping loop or band 21 having a pair of ears 22 between which an ear 23 formed integral with the holder 13a is adapted to be secured by means of a pivot 24. The ear 23 is frictionally secured between the ears 22 so that the shield and holder may optionally be swung upwardly and rearwardly to an inoperative position. In other respects the holder 13a is similar to the holder 13.

Referring now to Figures 7 and 8 there is disclosed another modified form of this invention wherein a holder 13b is provided similar to the holder 13, with the exception that the rear end

of the holder 13b has a U-shaped member 25 secured to or formed integral therewith which straddles the forward end of the handle 11b and a securing member 26 is extended through the parallel arms of the U-shaped member 25 and may also be extended through the blade 12b of the knife. In practice the securing member 26 may be one of the rivets or pins normally used to secure the handle to the knife blade.

Referring now to Figure 9 there is disclosed another modification of this invention wherein the holder 13c is provided with clamping arms 19c which are reversed from the clamping arms 19. In other words the clamping arms 19c extend over the top of the shield 14c. The rear end of the holder 13c includes a base 27 engaging over the back of the handle 11c and secured thereto by a fastening means 28.

In the use and operation of this device, the paring knife may be used in the normal manner for peeling onions or other vegetables and where such vegetables are juicy the shield 14 may be secured to the back of the knife, the clip 18 being slipped over the forward end of the handle 11 so as to support the holder 13 and the shield 14 along the back of the knife blade 12 with the shield disposed in forwardly divergent relation to the edge of the back of the knife, as shown in Figure 2. By having the shield spaced a slight distance from the knife, the latter may be used in the normal manner for peeling and cutting vegetables or the like. Preferably the shield is moist or damp when used as the shield when damp or moist more readily catches the fumes and juices that tend to smart the eyes. The provision of the absorbent shield will permit the juices to be absorbed and held with respect to the knife, and the shield may be readily cleaned by inserting the same in water or beneath a faucet. This device as hereinbefore described may be fixedly secured to a paring knife or may be used as a removable attachment for optional mounting on a knife.

I do not mean to confine myself to the exact details of construction herein disclosed, but claim all variations falling within the purview of the appended claims.

What I claim is:

1. As an article of manufacture an attachment for a knife having a handle and a blade, said attachment comprising an absorbent shield having substantial length and width, means secured to said shield and extending around the end thereof for supporting said shield lengthwise of and free from said blade, and a split band adapted to be disposed about the handle, said means being pivotally secured to said band, whereby said shield may be adjusted from an operative position lengthwise of said blade to an inoperative position rearwardly of said blade.

2. As an article of manufacture an attachment

for a knife having a handle and a blade, said attachment comprising an absorbent shield having substantial length and width, means secured to said shield and extending around the end thereof for supporting said shield lengthwise of and free from said blade, said means being operatively connected to the handle of the knife.

3. As an article of manufacture an attachment for a knife having a handle and a blade, said attachment comprising an absorbent shield having substantial length and width, means secured to said shield and extending around the end thereof for supporting said shield lengthwise of and free from said blade, said means including forwardly divergent clamping bars, said bars being operatively connected to the handle of the knife.

4. As an article of manufacture, an attachment for a knife having a handle and a blade, said attachment comprising a shield comprised of natural sponge having substantial length and width, means secured to said shield and extending around an end thereof for supporting said shield lengthwise of but spaced from said blade, and means connecting said last mentioned means to the handle of the knife.

5. As an article of manufacture, an attachment for a knife having a handle and a blade, said attachment comprising a shield comprised of sponge rubber having substantial length and width, means secured to said shield and extending around an end thereof for supporting said shield lengthwise of but spaced from said blade, and means connecting said last mentioned means to the handle of the knife.

6. As an article of manufacture, an attachment for a knife having a handle and a blade, said attachment comprising an absorbent shield having substantial length and width, means secured to said shield for supporting said shield lengthwise of and free from said blade, said means being operatively connected to the handle of the knife.

7. As an article of manufacture, an attachment for a knife having a handle and a blade, said attachment comprising a shield comprised of sponge rubber having substantial length and width, means secured to said shield for supporting said shield lengthwise of but spaced from said blade, and means connecting said last-mentioned means to the handle of the knife.

CHARLES H. HARVEY.
